ATTORNEY

UNITED STATES PATENT OFFICE

JULIUS M. SCHMEICHEL, OF PITTSBURGH, PENNSYLVANIA

SUSPENDERS

Application filed September 4, 1929. Serial No. 390,307.

My present invention has reference to what I will term a pair of concealed suspenders inasmuch as the same are worn beneath the shirt of the user and are attached 5 to the front buttons of the trousers by clamping the shirt thereto before the shirt is buttoned up its front, and the objects of the invention are the provision of a pair of suspenders of a construction whereby the 10 same may be easily, quickly and effectively adjusted, suspenders that will effectively brace the shoulders and the bones of the arm blades of the wearer to cause him to walk in an upright position but at the same 15 time permitting the free bending of his body, a pair of suspenders that will not only hold the shirt on the front buttons of the trousers but which has extending therefrom webbings provided with fastening means for 20 attaching the same to the hose of the user which not only affords an effective support for the hose but which holds the trousers in proper position and prevents the creasing thereof.

25 The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such 30 changes and modifications may be made therefrom as do not affect the spirit of the invention nor exceed the scope thereof as expressed in the appended claim.

In the drawings:

40 Figure 1 is a perspective view of the improvement, the same being indicated by dotted lines.

Figure 2 is a front elevation of the improvement.

45 As disclosed by the said drawings two

crossed straps are employed. For distinction the front portions of these straps are indicated by the numeral 17 and the rear portions by the numeral 18. The straps 17 and 18 cross each other at the back of the 50 suspenders and are connected together at their crossing points by a substantially rectangular tab 19. The ends of the front and rear portions 17 and 18 of the straps are disposed in close proximity to each other. 55 The ends of the front and rear portions 17 and 18 are folded upon themselves and are adjustably connected by clamps 20. The folded ends of the parts 17 and 18 of the straps have arranged therein loops 21. 60 These loops receive therethrough the folded ends of tabs 5'. The lower ends of the folded tabs 5' are provided with button engaging eyes 22. Each adjacent pair of tabs 5' is connected by a short strap or webbing 13, and stitched to the center of each of the webbings 13 there is a depending strap 14, the ends of each of the straps 14 being folded upon themselves and the said folded ends receive therethrough hose 65 engaging clamps 15. The ends of the straps 14 are adjustably connected by catches or clamps 16', so that the length of the straps 14 may be adjusted.

The device not only provides an effective 70 brace for the back and shoulders of the user, a means for supporting trousers, but also a means for supporting the hose of the wearer and likewise the straps 14 provide a means for holding the wearer's trousers in 75 properly creased condition.

Having described the invention, I claim:

A pair of suspenders comprising crossed 80 straps that afford front and back members which at their crossing points are connected together, said front and back members having their ends folded and provided with clamps for adjusting such ends, loops in the folded ends of the straps and the ends of 85 the respective pair of front and back mem- 90

bers being disposed in close proximity to each other, tabs connected to the loops adjacent the ends of the said front and back members, eye elements carried by the tabs, a short strap connecting each pair of tabs, a long strap centrally secured to each short strap, each of said long straps having their ends folded upon themselves and connected by an adjustable clamp and clasps in the folded ends of the long straps.

10 In testimony whereof I affix my signature.

JULIUS M. SCHMEICHEL.
